(57) **CLAIM**

The ornamental design for a controller for a vehicle heating and air conditioning system, as shown and described.

DESCRIPTION

FIG. 1 is a perspective front view of a controller for a vehicle heating and air conditioning system showing my new design;

FIG. 2 is a right side view of the controller for a vehicle heating and air conditioning system of FIG. 1;

FIG. 3 is a left side view of the controller for a vehicle heating and air conditioning system of FIG. 1;

FIG. 4 is a front elevation view of the controller for a vehicle heating and air conditioning system of FIG. 1,

FIG. 5 is rear elevation view of the controller for a vehicle heating and air conditioning system of FIG. 1;

FIG. 6 is a top elevation view of the controller for a vehicle heating and air conditioning system of FIG. 1;

FIG. 7 is a bottom elevation view of the controller for a vehicle heating and air conditioning system of FIG. 1; and, FIG. 8 is a perspective front view showing the movable selector arms of the controller in various positions.

In the drawings, any broken lines depict unclaimed subject matter only and form no part of the claimed design.
